ADJUSTABLE BED
Paulus Henricus Maria Schilte, 60 Herkimer St.,
Hamilton, Ontario, Canada
Filed Aug. 13, 1965, Ser. No. 479,389
7 Claims. (Cl. 5—202)

The invention relates to an adjustable bed and in particular, to an adjustable bed of the type which may be used either with or without a mattress, especially in emergency or temporary uses.

Conventional bed design has for many years comprised a bed spring providing an essentially flexible support and a mattress with or without additional springs supported on the bed spring. This design severely restricts the free circulation of air around the body and tends to cause perspiration, especially when, as in institutions, the bed is occupied for any length of time. In addition, beds of this type are virtually incapable of adjustment to suit different persons thus requiring either the use of a single standardized springing for all persons which is obviously unsatisfactory, or acquiring the manufacture of a number of different beds and mattresses having different degrees of springing, which tends to be relatively expensive. In addition, conventional mattress design involves continual discarding and replacement of mattresses at a relatively high expense, particularly in institutions such as hospitals, nursing homes and the like.

A further disadvantage is the difficulty of storing conventional beds. In the majority of cases, both the bed spring and the mattress are of approximately equal depth and require a very considerable storage space since they cannot be stored in a reduced space by folding.

Accordingly, it is an objective of the present invention to provide an improved bed which is readily adjustable to suit different sizes of persons and which may be used either with or without a mattress, being especially designed for use without a mattress in the majority of cases.

More particularly, it is an objective of the present invention to provide a bed having the foregoing advantages having a construction which is particularly adapted to nesting when not in use for storage.

More particularly, it is an objective of the present invention to provide a bed having the foregoing advantages in which the resilient springing members thereof may be readily replaced as they wear with a minimum of cost.

More particularly, it is an objective of the present invention to provide a bed having the foregoing advantages incorporating means extending around the edge of the bed for retaining the bed clothes in position thereon, especially when the bed is used without a mattress.

More particularly, it is an objective of the present invention to provide a bed having the foregoing advantages having improved facilities for ventilation around the entire body of the occupant.

The foregoing and other advantages will become apparent from the following description of a preferred embodiment of the invention which is here given by way of example only and with reference to the following drawings in which like reference devices refer to like parts thereof throughout the various views and diagrams, and in which:

FIGURE 1 is a top plan view of a bed according to the invention;

FIGURE 2 is a greatly enlarged detail top plan view of the corner of the bed of FIGURE 1 enclosed by the lines 2—2;

FIGURE 3 is a side elevational view, partly broken away of the corner of the bed shown in FIGURE 2;

FIGURE 4 is a sectional side elevation of the bed of FIGURES 1, 2 and 3 along the line 4—4 of FIGURE 2;

2

FIGURE 5 is a sectional side elevation of a further embodiment of a bed, corresponding to the position of the section of FIGURE 4;

FIGURE 6 is a plan view of a central portion of a bed 5 according to the invention showing a further embodiment;

FIGURE 7 is a sectional side elevation of a further embodiment of the invention and showing the side edge of a bed in a location corresponding to the position of FIGURE 4;

FIGURE 8 is a sectional side elevation along the line 8—8 of FIGURE 6;

FIGURE 9 is a plan view of a detail of the embodiment of FIGURE 6 shown in isolation; and

FIGURE 10 is a partial sectional side elevation of a further embodiment.

Referring now to FIGURES 1 to 4 it will be seen that this preferred embodiment of the bed consists of an upper frame 10 and a lower frame 11, the upper frame 10 being smaller than the lower frame 11. These frames 10 and 11 are of tubular construction, and are rectangular in shape. They have rounded corners 12 and 13 respectively. Both frames 10 and 11 lie in parallel planes and centre on a common axis. Each frame 10 and 11 have a series of holes 14 and 15 respectively, drilled through the cross-section of the tubes, one at each corner and at equally spaced intervals between corners. The holes 14 and 15 are in axial alignment with each other and are dimensioned to permit spacer bars 16 to fit therein joining the frames 10 and 11 by passing through the holes 14 and 15 and being welded in place therein. While the frames 10 and 11 may vary in relative size so that the spacer bars 16 appear at various angles it is preferred that the frames 10 and 11 be of such a proportion to each other that the spacer bars 16 are at an angle of about 45° to the planes of frames 10 and 11. At this angle the beds may be stacked one inside the other taking up the minimum of space for storage when not in use. The resilient support means of this invention, providing both bed spring and mattress comprises strips of rubber or rubber like plastic webbing 17 and 18 having a certain give or elasticity interwoven over and under normal to each other and are placed over the upper frame 10. The ends of the strips of webbing 17 and 18 are folded over the upper frame 10 around a loose pincher bar 19 and then up and over a fixed bar 20. The fixed bar 20 is welded to the spacer bars 16 at a distance 21 from the upper frame 10 so that a double thickness of webbing 17 or 18 may pass through the space 21. The pincher bar 19 must be of sufficient diameter that it will not fall through the space 21 when only a single thickness of webbing 17 or 18 is used. The means for clipping or fastening the bedding comprises spring clips 22 bent to partially enclose the lower frame 11 and having extensions 23 normally lying approximately parallel to the spacer bars 16. The upper end of the extension 23 is folded back on itself to form a rectangular shaped loop 24. A rubber or rubber-like plastic belt 25 for holding the bedding (not shown) is retained in position by the loop 24.

Referring now to FIGURE 5, it will be noted that in this preferred embodiment of the bed the upper frame 10 is larger than the lower frame 11. In this form the bed is preferred for permanent use such as in a hospital ward or nursing home, etc., as doctors, nurses, etc., will not have to reach over to work on a patient, also the leg of the bed will be out of the way as will be apparent later.

Referring now to FIGURES 6, 7, 8 and 9, it may be desirous to have an opening in the surface of the bed over a given area of the body for medical or hospital treatment, in such cases an opening indicated generally as 26 can be provided in the webbing 17 and 18. This is achieved during the assembly of the bed by providing an

opening ring 27 made of circular stock bent to form a square or rectangle of such a size that one side of the square or rectangle will hold three or more strips of webbing 17 and 18. The webbing 17 and 18 is folded around the opening ring 27 and back under itself as 17a and 18a.

The supporting means of the instant bed are illustrated in FIGURE 10. The lower frame 11 has tapped holes 28 in it at right angles to the plane of the bed to allow insertion of a tubular leg 29, the upper portion of which is threaded 30 for attachment to the frame 11. A foot 31 is welded to the bottom of the leg 29. This is but one method of fastening a leg to the frame as many variations are adaptable to those skilled in the art including the provision of folding legs by any suitable means (not shown) for ease of storage.

In operation, the legs 29 are attached to the frame 11. This assembly is set up on its feet. Rubber webbing 17 is laid across the frame. One end of the webbing 17 is folded over the end of the frame 10, around the loose pincher bar 19 and then up and over the fixed bar 20 and pulled tight enough to lock it in place. This operation is then repeated at the opposite end of the frame. Then webbing 18a is interlaced through the webbing 17 and at right angles to it. The webbing 18 is now locked in place in the same manner as before. The free ends of webbing 17 and 18 are now pulled until the desired tension is obtained. It will be noted that the tension can be varied for different sections of the bed as each strip of webbing 17 and 18 can be adjusted independently. If it is desired to have a hole 26 in the bed, webbing 17 and 18 in the preferred area of the hole is fastened to one side of the frame only, the loose ends 17a and 18a being folded over the opening ring 27 and brought back under the top layer of webbing 17 and 18 and locked in place as before. Another strip of webbing 17 and 18 is then placed at the opposite side of the opening ring and dealt with similarly.

The bed is now ready to be covered with sheets, blankets or other bedding. The skirt or overhang of the bedding is tucked under the tape 25 that encircles the bed, thus holding the bedding in place. To disassemble, the reverse procedure is followed, then the unit can be stored. As in one of its preferred embodiments the units can be stacked one inside the other, thus occupying a minimum of space.

The foregoing is a description of a preferred embodiment of the invention which is here made by way of example only. The invention is not to be taken as limited to the specific steps described but comprehends all such variations that come within the spirit and scope of the appended claims.

I claim:

1. An adjustable bed assembly for use with persons of differing body weight and comprising: a rectangular bed frame having side and end portions and means for supporting said frame; strips of elastic resilient material extending from side to side and end to end of said bed frame interwoven with one another defining together a resilient body-engaging surface; a rectangular bed support frame having side and end portions, said frame being of different dimensions from said bed frame; frame junction members extending between said bed frame and said support frame and spacing the same apart from one another in parallel planes; a tension rod member fastened to said junction members parallel to said side and end portions of said bed frame and spaced therefrom a predetermined distance; and clamping rod means of a cross-sectional dimension about equal to or greater than said predetermined distance and normally held adjacent to said tension rod by engagement with said strip material.

2. The apparatus as claimed in claim 1, including means defining an opening in said interwoven strip material.

3. The apparatus as claimed in claim 1, including fabric gripping band means extending around said bed frame spaced therefrom for engagement of bed clothes on said bed.

4. The apparatus as claimed in claim 3, including resilient band supporting members of spring metal locating same in position as aforesaid.

5. The apparatus as claimed in claim 1, including leg means mounted on said support frame.

6. The apparatus as claimed in claim 1, wherein said support frame is of a greater size than said bed frame.

7. The apparatus as claimed in claim 1, wherein said support frame is of a smaller size than said bed frame.
